UNITED STATES PATENT OFFICE

JULIAN EARL MONTGOMERY, OF WHEELING, WEST VIRGINIA.

ROLLING-MILL COUPLING.

1,189,609.

Specification of Letters Patent. Patented July 4, 1916.

Application filed December 27, 1915. Serial No. 68,759.

To all whom it may concern:

Be it known that I, JULIAN EARL MONTGOMERY, a citizen of the United States, residing at Wheeling, in the county of Ohio and State of West Virginia, have invented a new and useful Rolling-Mill Coupling, of which the following is a specification.

The present invention appertains to rolling mill couplings, and aims to provide a novel and improved coupling device for connecting the spindle with the roll of a rolling mill, the device being designed for taking up the wear, for holding the spindle and coupling box in proper position relative to one another, to prevent backlash when a train of rolls are coupled together and to hold the coupling box in proper engagement with the roll.

When the coupling boxes and spindles become worn, they permit the rolls to run ahead and cause a sudden stop just as the piece which is being rolled leaves the rolls, which results in a backlash due to the roll's advanced speed ahead of the spindle, and it is the object of the invention to prevent the rolls from getting ahead of the spindles, by keeping the coupling box tight against the driving side of the spindle.

The present device is adjustable and also enables the coupling box to be slipped back on the spindle when the roll is removed or replaced.

It is also within the scope of the invention to provide a device of the nature indicated which is comparatively simple and inexpensive in construction, which can be readily used in rolling mills without entailing prohibitive trouble and expense, and which will serve its office in a thoroughly practical and efficient manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a side elevation of the coupling device constructed in accordance with the invention. Fig. 2 is a cross section taken on the line 2-2 of Fig. 1. Fig. 3 is a sec-

tional detail taken on the line 3-3 of Fig. 1. Fig. 4 is a fragmental detail illustrating the fork.

In the drawings, there is depicted the coupling box or member 1 which is of cylindrical form, and which couples together the adjacent ends of the spindle 2 and roll 3 of the rolling mill, said spindle and roll being in alinement or being coaxial, the neck of the roll 3 only being illustrated. The adjacent end portions of the spindle and roll are of cruciform or non-circular cross section, as at 4 and 5, respectively, and the coupling box 1 is provided with a longitudinal opening 6 extending from end to end, and of cruciform or non-circular contour to loosely receive the adjacent ends of the spindle and roll, whereby to connect them for simultaneous rotation, the roll being driven by the spindle. The spindle 2 is provided with an outstanding annular flange or collar 6 between the portion 4 and the body portion of the spindle which is cylindrical. The foregoing parts are common in rolling mills, but used by themselves, are objectionable for the reasons above indicated and for other familiar reasons.

In carrying out the present invention, the spindle end of the coupling box 1 is provided with a plurality, in this case four, of outstanding lugs 7 projecting within the angular recesses of the portion 4 of the spindle, and provided with cored openings or bores 8 perpendicular to certain walls of said recesses. Disposed in each opening 8 is a coiled expansion spring 9 having one end bearing against the respective wall of the portion 4, and having its other end bearing against a spring head 10 fitting loosely within the outer end of the opening 8 and having an inwardly projecting lug 11 entering the respective end convolution of the spring to center the spring and head 10 relative to one another. The heads 10 have outstanding lugs or bosses 12.

Mounted for rotation upon the spindle end of the box 1 is a ring 13 having four inwardly projecting cams 14 at its outer edge overlapping the spindle end of the box 1, and bearing against the studs 12, so that when the ring 13 is rotated in one direction, the cams 14 will force the heads 10 into the openings 8 further, thereby compressing the springs 9 and increasing the tension thereof.

The spindle end of the box 1 has a pair of diametrically opposite outstanding lugs

15 through which adjusting screws 16 are threaded to bear against the ends of two diametrically opposite cams 14, whereby when said screws 16 are projected from the lugs 15, they will rotate the ring 13 in the direction for bringing the springs 9 under greater tension. When the screws 16 are retracted to remove the cams 14 from the bosses 12, the ring 15 can be slipped off of the box 1 and moved back onto the spindle.

10 In order to yieldably move the coupling box 1 into engagement with the end portion or wobble 5 of the roll 3, spring means are disposed between the spindle and coupling box, and to this end a pair of diametrically opposite lugs 7 are each provided remote from the box 1 with a pair of outstanding ears 17 and the web 18 therebetween and of shorter length than the ears 17. The end fork 19 of a bolt or rod 20 straddles the web 18 between the ears 17, to be held in place thereby, and adjusting nuts 21 are threaded upon the bolt 20. A coiled expansion spring 22 is disposed between the nuts 21 of each bolt 20 and the shoulder 26 formed by the collar 6 at the respective ends of the recesses of the portion 4, centering pins 24 being threaded into the shoulder 23 for holding the adjacent ends of the springs 22 in place. By adjusting the nuts 21, the tensions of the springs 22 can be adjusted as desired, and said springs in tending to expand will force the coupling box 1 away from the spindle toward the roll, thereby holding the box and roll assembled, to prevent their accidental detachment.

40 When it is desired to remove or replace the roll, it is necessary to slip the box 1 back onto the spindle, and this can be readily done by disengaging the forks 19 from the webs 18, the nuts 21 being loosened if necessary. Then, when the bolts 20 and springs 22 are removed, the box 1 can be moved freely to retracted position, whereby 45 the roll can either be removed or applied whichever is the case.

50 When the ring 13 is adjusted for compressing the spring 14, the tension of said springs will rotate the spindle and box relative to one another, until the respective walls or driving surfaces of the spindle and box contact, and said springs will hold said walls and surfaces in contact under all conditions, thereby preventing loose play, backlash, 55 wear and tear, and the like, the tensions of the springs being readily adjusted as above indicated.

60 The parts may be readily assembled and separated, and can be inexpensively manufactured and installed.

65 It is to be noted that the springs 22 permit the spindle and roll to yield longitudinally or axially relative to one another, and this is of special advantage when a series of rolls are coupled together, for should one

roll break at an angle, to force the sections thereof apart longitudinally, the springs 22 would give and thus prevent end thrust on other rolls.

Having thus described the invention, what is claimed as new is:

1. In a device of the character described, a coupling box, a spindle engaged therewith and having a portion of angular cross section fitting in said box and providing a recess, a coiled spring having one end bearing against one wall of said recess, and means carried by said box against which the other end of the spring bears, said spring serving to hold the driving surfaces of the box and 75 spindle in contact.

2. In a device of the character described, a coupling box, a spindle having a portion of angular cross section fitting in said box and providing a recess, the box having a 85 lug projecting therefrom within said recess, and having an opening, a coiled spring within said opening and bearing against one wall of said recess, and means carried by the box for compressing said spring.

90 3. In a device of the character described, a coupling box, a spindle engaged therewith, a plurality of springs carried by one of said parts and bearing against the other, and means for simultaneously adjusting all 95 of the springs, said springs when brought under pressure serving to hold the driving surfaces of the box and spindle in contact.

4. In a device of the character described, a coupling box, a spindle engaged therewith, 100 a plurality of springs carried by one of said parts and bearing against the other for holding the driving surfaces of said parts in contact, and a cam ring rotatable upon one of said parts for adjusting the pressure of all 105 of the springs simultaneously.

5. In a device of the character described, a spindle, a coupling box fitted thereon, one of said parts having a plurality of lugs provided with openings, expansion springs disposed within said openings and bearing against the other of said two first mentioned parts, and a rotatable cam ring upon one of said parts and adjustable for compressing said springs simultaneously.

110 6. In a device of the character described, a coupling box, a spindle having a portion of angular cross section fitting in said box and provided with recesses, said box having lugs projecting from one end within said recesses, 120 and springs carried by said lugs and bearing against certain walls of said recesses to hold the driving surfaces of the spindle and box in contact.

125 7. In a device of the character described, a spindle having an end portion of angular cross section, a coupling box fitted upon said end portion and having lugs projecting from one end and provided with openings, compression springs in said openings bearing 130

against said spindle, heads working within said openings and bearing against the springs, a rotatable ring upon said end of said box and having cams coöperable with 5 said heads, and means for adjusting the ring relative to the box for compressing said springs.

8. In a device of the character described, a coupling box, a spindle having an end portion of cruciform cross section fitted within said box, one end of said box having outstanding lugs within the recesses of said end portion, said lugs having openings, coiled 10 expansion springs in said openings and bearing against certain walls of said recesses, spring heads working within said recesses and bearing against those ends of the springs remote from said walls, a ring rotatable upon said end of said box and having inwardly projecting cams coöperable with said heads, said box having another lug outstanding from said end thereof, and an adjusting screw threaded through the last mentioned lug and bearing against one of said cams for 15 rotating said ring to compress said springs.

9. In a device of the character described, a spindle having a shoulder, a boxing fitting slidably upon the end of said spindle, bolts 20 detachably engaged with said box, nuts 25

threaded upon said bolts, and expansion 30 springs between said nuts and shoulder.

10. In a device of the character described, a spindle having a shoulder, a coupling box fitted slidably upon the end of said spindle and having at one end pairs of ears and a 35 web between each pair of ears, bolts having forks straddling said webs between the ears, nuts threaded upon said bolts, coiled expansion springs between said nuts and shoulder, and pins carried by said shoulder for holding 40 the adjacent ends of said springs in place.

11. In a device of the character described, a spindle having a cruciform end portion and a shoulder adjacent the same, a coupling box 45 slideable upon said end portion of the spindle and having outstanding lugs at one end within the recesses of said end portion, springs carried by said lugs and bearing against certain walls of said recesses, and detachable spring means between certain of 50 said lugs and said shoulder within the respective recesses, to move the box away from the spindle.

In testimony that I claim the foregoing as 55 my own, I have hereto affixed my signature.

JULIAN EARL MONTGOMERY.
